UNITED STATES PATENT OFFICE.

WILLIAM GEIB, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A METAL BASKET OR SIMILAR ARTICLE.

Application filed October 24, 1922. Serial No. 4,074. Term of patent 7 years.

To all whom it may concern:

Be it known that I, WILLIAM GEIB, a citizen of the United States, residing at Meriden, in the county of New Haven and State of Connecticut, have invented a new, original, and ornamental Design for a Metal Basket or Similar Article, of which the following is a specification, reference being had to the accompanying drawing, forming a part thereof.

The figure is a view in perspective of a metal basket showing my new design.

I claim:

The ornamental design for a metal basket or similar article as shown.

WM. GEIB.
